(57) **CLAIM**

The ornamental design for a tool storage rack, as shown and described.

DESCRIPTION

FIG. 1 is a first perspective view of a tool storage rack showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is the using state of the tool storage rack thereof; and,
FIG. 10 is an enlarged view of the selected portion **10** in
FIG. 1.

The dash-dash broken lines shown in the drawings depict
portions of the tool storage rack that form no part of the
claimed design. The dot-dash broken lines in FIGS. 1 and **10**
illustrate the periphery of the enlarged views of the tool
storage rack and form no part of the claimed design.
